UNITED STATES PATENT OFFICE.

JOSEPH G. SWALLOW, OF BROOKLYN, NEW YORK, ASSIGNOR OF ONE-THIRD TO WALTER E. MCCOY AND ONE-THIRD TO FRANK W. SMITH, BOTH OF NEW YORK, N. Y.

CUT-OUT.

946,409.

Specification of Letters Patent. Patented Jan. 11, 1910.

Application filed June 6, 1908. Serial No. 437,152.

To all whom it may concern:

Be it known that I, JOSEPH G. SWALLOW, a citizen of the United States of America, and residing in the borough of Brooklyn, 5 county of Kings and State of New York, have invented certain new and useful Improvements in Cut-Outs, of which the following is a specification.

My invention relates to cut-out blocks for 10 electric connectors and particularly to fusible cut-outs, the object of my invention being to provide a device of this character adapted to receive fuses of different characters and sizes.

15 In the accompanying drawings, Figure 1 is a plan of a block in which my invention is incorporated; Fig. 2 is a section thereof on the line 2—2, Fig. 1; and Fig. 3 is a similar section of a combined cut-out and switch.

20 In order to accommodate either plug or cartridge fuses, I mount upon the insulating base A and between the clips 5 and 6 for a cartridge fuse, a plug receptacle 7 of the usual type. The current is led from the screw shell 8 to the clip 6 by a connecting strip 9, while a similar strip 10, leads the current from the plug terminal 11 to the 25 opposite clip 5. Finger room for the insertion of the plug is provided by suitably recessing the insulating fins 23, which separate adjacent clips. It is obvious that the connection between the clips is thus as readily made by inserting a fuse plug in the receptacle 7 as by adjusting a cartridge fuse 30 between the clips 5 and 6.

35 As the preferred construction, I have shown the cut-out with grooves 12 for the line wires and the current is led from the latter by conducting strips 13 located in recesses in the back of the porcelain and angled up at one end to the point of contact 40 with the wire, while a screw 15 unites the opposite end of the strip 13 with a plate 16, electrically connected to the clip 6. A similar plate 17 leads the current from the clip 5 to the service wire binding post 18.

45 A series of threaded holes 19 are formed in the plates 16 and 17 to receive binding screws 20. By means of these a naked fuse 50 may be inserted but they are primarily intended for cartridge fuses of the screw clamp type and of different lengths. If necessary when fuses of this sort are employed, the clips 5 and 6 may be removed

by unscrewing the nuts 21 by which they are 55 secured to the bolts 22. To obviate the necessity for removing the clips however, the plates 16 and 17 are offset at the point at which the clips are attached so as to form a shoulder against which the end of the cartridge abuts, while its perforated or slotted wings extend beyond at each end to the binding posts. A recess 24 may be formed beneath the holes 19 to permit the binding screw to be turned down tight when not in 60 use.

The cut-out may be combined in any suitable manner with other devices—for example switches, as shown in Fig. 3. When the cut-out is thus combined with a switch, the 70 strips 13 may be eliminated and one terminal of the switch connected directly to the plate 16 as shown.

Modifications of my device may be readily devised and I do not limit myself to the precise construction shown.

I claim as my invention:

1. A cut-out block having a plug receptacle and means independent thereof for carrying a substantially horizontal fuse 80 above the same.

2. A cut-out block having a plug receptacle and means independent thereof for carrying a substantially horizontal cartridge fuse above the same.

3. A cut-out block having an insulating base recessed to receive a fuse plug receptacle and means to carry a fuse above said receptacle.

4. A cut out block having wire terminals, 90 spring clips to receive a cartridge fuse of one type and binding posts to secure a cartridge fuse of different type and connections from said clips and binding posts to the respective terminals whereby a fuse of either 95 character may be inserted between the latter, substantially as described.

5. A cut out block having wire terminals, 100 spring clips to receive a cartridge fuse of one type and binding posts to secure a cartridge fuse of different type and connections from said clips and binding posts to the respective terminals whereby a fuse of either character may be inserted between the latter, together with means for spacing said binding posts apart to different distances to accommodate fuses of different lengths.

6. A cut out block having wire terminals,

conducting straps extending therefrom and spring clips to receive the opposite ends of a cartridge fuse being connected to said straps, the latter being perforated to receive 5 binding screws for connecting cartridge fuses of a different type to said straps.

7. A cut-out block having a fuse plug receptacle and terminals for a cartridge fuse and electrical connections through the latter 10 to the different terminals of the plug receptacle.

8. A cut out block having circuit terminals, plug terminals, cartridge fuse terminals independent thereof and connections 15 from said plug and cartridge fuse terminals to the circuit terminals whereby the circuit between said terminals is directly completed through a fuse of either type connected to its appropriate terminals.

20 9. A cut out block having circuit terminals, plug terminals, cartridge fuse terminals for different types of cartridge fuses independent thereof and connections from said plug and cartridge fuse terminals to 25 the circuit terminals whereby the circuit between said terminals is directly completed through a fuse of desired type connected to its appropriate terminals.

10. A cut out having a base of insulating 30 material, conducting straps mounted thereon and connected to circuit terminals, terminals for a cartridge fuse on said straps, independent plug terminals on said base and connecting strips leading from said conducting straps to the respective plug terminals, 35 whereby a circuit may be completed between said circuit terminals by the insertion of

either a plug or a cartridge fuse, substantially as described.

11. A cut-out block having connected to a 40 circuit terminal a plate provided with a plurality of threaded holes, and a terminal screw adapted to be adjusted in said holes to accommodate different sizes of cartridge fuses provided with means to engage said 45 screw in combination with means connected with the other circuit terminal adapted to receive the other end of said cartridge fuse together with terminals for a plug fuse interposed between said plates and electrical 50 connections thereto respectively.

12. A cut -out block having terminal plates with a plurality of threaded perforations to receive adjustable terminal screws for each plate, a clip for a cartridge fuse 55 connected to each plate and an interposed fuse plug receptacle with connections from the terminals thereof to said plates, substantially as described.

13. A cut -out block having terminal 60 plates with a plurality of threaded perforations to receive adjustable terminal screws for each plate, a clip for a cartridge fuse detachably connected to each plate and an interposed fuse plug receptacle with connections from the terminals thereof to said plates, substantially as described.

In testimony whereof I have signed my name to this specification, in the presence of two subscribing witnesses.

JOSEPH G. SWALLOW.
